UNITED STATES PATENT OFFICE.

HANS R. SETZ, OF MANITOWOC, WISCONSIN.

CYLINDER FOR INTERNAL-COMBUSTION ENGINES.

Application filed April 11, 1921 Serial No. 460,534.

To all whom it may concern:

Be it known that I, HANS R. SETZ, a citizen of the United States, residing at Manitowoc, Wisconsin, have invented a certain 5 new and useful Improvement in Cylinders for Internal-Combustion Engines, of which the following is a full, clear, and exact description, such as will enable others skilled in the art to which it appertains to make 10 and use the same.

This invention relates to cylinders for two cycle internal combustion engines of the kind in which scavenging ports and exhaust ports are arranged in the inner wall of the 15 cylinder in proximity to each other.

The main object of my invention is to provide an engine cylinder of the general type referred to which is so constructed that the inner wall of same will not warp out 20 of its true axial position, due to the unequal heating of the two portions of the inner wall that contain the exhaust and scavenging ports.

To this end I have devised an internal 25 combustion engine cylinder having an inner wall equipped with exhaust ports and scavenging ports arranged in a zone common to both sets of ports and composed of a plurality of sections that are separated 30 from each other by a space or joint which permits said sections to expand and contract longitudinally with relation to each other sufficiently to compensate for the relatively higher temperature of that portion 35 of the inner wall of the cylinder in which the exhaust ports are formed. The inner wall of the cylinder is preferably formed by two liners or open-ended cylindrical members arranged end to end and separated 40 from each other by a joint or space that extends circumferentially around the cylinder in the zone that contains the scavenging ports and exhaust ports, and a supporting means is provided for said liners to which 45 the outer end portions of the liners are rigidly connected, thereby permitting the inner end portions of the liners that contain the ports to expand and contract longitudinally with relation to each other when the 50 engine is in operation.

In the form of my invention herein illustrated the supporting means in which the cylinder liners are arranged and to which the outer end portions of said liners are rigidly connected consists of an outer jacket 55 wall provided with means for cooling the

parts of the inner wall of the cylinder that lie between the ports, said cooling means preferably consisting of water cooled portions on the outer jacket wall that back up 60 the parts of the inner wall lying between the ports, and thus prevent said parts from acquiring excessively high temperatures. The joint or space between the inner ends of the two liners or sections that constitute 65 the inner wall of the cylinder can be formed in various ways without departing from the spirit of my invention, and any suitable means can be employed to prevent communication from the exhaust port side of 70 the cylinder to the scavenging port side of the cylinder through the expansion gap or joint between the two cylinder liners.

Figure 1 of the drawings is a vertical longitudinal sectional view of a double acting cylinder for two cycle internal combustion engines constructed in accordance with 75 my invention.

Figure 2 is a horizontal sectional view, taken on the line A—A of Figure 1. 80

Figure 3 is a vertical longitudinal sectional view, illustrating a slight modification of my invention applied to a single acting cylinder; and

Figure 4 is a fragmentary horizontal section of the cylinder shown in Figure 3, taken along the line B—B of Figure 3. 85

Referring to Figures 1 and 2 of the drawings, 1 and 2 designate two liners or open-ended tubular members arranged end to end 90 so as to form the inner wall of a cylinder, and 3 designates a supporting means in which said liners are mounted. In the form of my invention herein illustrated the supporting means 3 consists of an outer jacket 95 wall to which the outer end portions of the liners 1 and 2 are rigidly connected by fastening devices 3^a, or in any other suitable manner, that will permit the inner end portions of said liners to expand and contract 100 longitudinally with relation to each other. The inner ends of the liners 1 and 2 are separated from each other by a gap 4 of sufficient width to permit unrestricted expansion of said liners under the influence of the 105 working temperatures, and exhaust ports 5 and scavenging ports 6 are arranged in the inner wall of the cylinder preferably opposite each other, as shown in Figure 1, said ports being formed by slots cut through the 110 inner end portions of both sections or liners of the cylinder and of such shape that they

co-operate with each other to form oblong or rectangularly-shaped ports when the two sections 1 and 2 are in operative position in the belt section 3. The portion of the outer jacket wall 3 which surrounds the zone of the inner wall of the cylinder that contains the exhaust ports and scavenging ports 5 and 6, respectively, is provided with corresponding ports or openings, and said outer jacket wall is preferably equipped with water cooled portions 7 and 8 that respectively back up the parts 7^a of the inner wall of the cylinder lying between the exhaust ports 5 and the parts 8^a of the inner wall of the cylinder lying between the scavenging ports 6. The water cooled portions 7 and 8 of the outer jacket wall 3 are continuous and are in direct communication with the water jackets formed by the annular space α between the cylinder liner 1 and the upper portion of the outer jacket wall 3 and the annular space γ formed between the liner 2 and the lower portion of the jacket wall 3, said liners being provided at their inner ends with portions that are slidably fitted in the intermediate portion α of the outer jacket wall 3. In view of the fact that the water cooled portions 7 and 8 of the outer jacket wall 3 are in direct contact with the vertically-disposed bar-like parts 7^a and 8^a of the inner wall of the cylinder that lie between the ports, said parts will be effectively cooled, notwithstanding the fact that said parts are of such construction that they can expand and contract longitudinally.

With such a construction each of the vertically-disposed bar-like parts of the inner wall of the cylinder lying between two ports is permitted to go through its own unrestricted process of contraction and expansion, according to the temperature to which it is exposed, due to the function of the ports between which it is arranged. Thus the bar-like parts which are arranged between the exhaust ports will naturally get hotter than the corresponding parts between the scavenging ports and are permitted to expand in accordance with their mean temperature. At the same time the water cooled portions 7 and 8 of the outer jacket wall 3, by virtue of the fact that they back up the uncooled parts 7^a and 8^a, respectively, of the inner wall of the cylinder, prevent the latter from acquiring excessively high temperatures. Consequently, warping of the cylinder out of its true axial position is eliminated.

The expansion gap or joint 4 between the two sections 1 and 2 constituting the inner wall of the cylinder is preferably made irregular or of such form that the expansion joints between the consecutive bar-like parts of the inner wall between the ports are staggered so as to facilitate easy travel of the piston rings over the joint between the two liners 1 and 2. Provision is also made to

prevent communication from the exhaust port side of the cylinder to the scavenging port side through the expansion gap 4, and in the form of my invention shown in Figures 1 and 2 this is accomplished by interrupting the gap 4, as shown in Figure 1, and providing the cylinder liner 1 with portions 1^a having vertically-disposed surfaces that bear snugly against and slide upon vertically-disposed surfaces on portions 2^a on the liner 2. With an expansion joint of the form above described it is possible for the liners 1 and 2 of the cylinder to expand and contract longitudinally with relation to each other without liability of communication being established between the two parts of the expansion gap lying on opposite sides of the vertical contact surfaces on the co-operating portions 1^a and 2^a of the cylinder liners.

In Figures 3 and 4 of the drawings I have illustrated a single acting cylinder for two cycle internal combustion engines that has the same desirable features and characteristics of the cylinder shown in Figures 1 and 2, but provided with a different means for preventing the expansion gap from establishing communication between the two sides of the cylinder in which the scavenging ports and exhaust ports are formed. In the form of my invention shown in Figures 3 and 4 axially-disposed key pieces 9, only one of which is shown, are inserted between the co-operating portions 1^a and 2^a of the cylinder liners 1 and 2, respectively, thus providing sliding contact surfaces which permit longitudinal expansion and contraction of either liner, but effectively cutting off communication between the exhaust ports and scavenging ports. Any suitable means can be used for retaining the key pieces 9 in position, such, for example, as machine screws 10 inserted from the outside of the belt section 3, as shown in Figure 4.

It is, of course, immaterial, so far as my broad idea is concerned, how the cylinder sections or liners 1 and 2 are mounted, so long as they are mounted in such a manner that the inner end portions of same in proximity to the exhaust and scavenging ports can expand and contract longitudinally with relation to each other. For example, in Figures 1 and 2, the liners 1 and 2 are of cylindrical form and are centered at their outer ends in bored seats in a supporting means 3 and rigidly connected to same by fastening devices 3^a which pass through flanges on the outer ends of said liners. Or the liners can be mounted in the manner illustrated in Figures 3 and 4, wherein each of the liners is provided at its outer end with an integral, short outer wall jacket section that bears upon the supporting means or outer jacket wall 3 and is rigidly connected to same by fastening devices 3^a. Likewise, the formation of the scavenging and exhaust

ports in the outer jacket wall 3 is immaterial, so far as my broad idea is concerned. Thus, instead of making the scavenging ports in the outer jacket wall 3 in the form of individual radial passages that align with the scavenging ports 6 in the inner wall of the cylinder, the scavenging ports in the outer jacket wall may consist of short radial openings leading into a common passage similar 5 to that on the exhaust port side of the cylinder. While I prefer to make the exhaust outlet in the outer jacket wall 3 in the form shown in Figure 2, namely, provide said exhaust outlet with a center water cooled portion 10 7^b running clear through to the outer face of the cylinder, and thus virtually producing two exhaust outlets, this is not essential, for if desired, said partition 7^b can be replaced by a water cooled portion similar 15 to the water cooled portions that back up the parts 7^a of the inner wall located between the exhaust ports 5 of the cylinder.

Having thus described my invention, what I claim as new and desire to secure by Letters Patent, is:

1. A cylinder for two cycle internal combustion engines, comprising an inner wall composed of two separate sections arranged in axial alignment, scavenging and exhaust 30 ports formed in the adjacent ends of said inner wall sections, and an outer wall section provided with ports that coordinate with the ports in said inner wall and having portions in engagement with the inner wall 35 portions lying between said ports.

2. A cylinder for two cycle internal combustion engines, comprising an inner wall composed of two separate sections arranged in axial alignment, scavenging and exhaust 40 ports formed in the adjacent ends of said inner wall sections, an outer wall section provided with ports that coordinate with the ports in said inner wall, and water-cooled portions on said outer wall section that bear 45 directly against the portions of the inner wall lying between the ports therein.

3. A cylinder for two cycle internal combustion engines having an inner wall equipped with exhaust ports and scavenging ports arranged in a common plane in opposite sides of said inner wall and composed of two sections arranged end to end and separated from each other by an expansion gap or joint that extends circumferentially around the cylinder through said ports, and 50 means for preventing said expansion gap from establishing communication between the ports in the opposite sides of the inner wall of the cylinder.

4. A cylinder for two cycle internal combustion engines having an inner wall equipped with oppositely-disposed exhaust ports and scavenging ports and composed of two liners arranged end to end and separated from each other by an expansion joint 65 that extends circumferentially of the cylinder in proximity to said ports, an outer jacket wall to which the outer end portions of said liners are rigidly connected and provided with means in which the inner end 70 portions of said liners are slidably fitted, water cooled portions on said outer jacket wall that bear directly against and thus back up the parts of the inner wall of the cylinder lying between the ports in said wall, and 75 means for preventing said expansion joint from establishing communication between the exhaust ports and scavenging ports.

5. A cylinder for two cycle internal combustion engines, comprising an inner wall 80 composed of two sections arranged in axial alignment and separated from each other by a circumferentially-disposed expansion gap, scavenging and exhaust ports in the adjacent ends of said inner wall sections, an outer 85 jacket wall surrounding the inner wall sections in the zone of said ports, and means for preventing communication between the exhaust and scavenging ports through said expansion gap.

HANS R. SETZ.
